CLAIM

The ornamental design for an environmental enclosure for housing cellular RF equipment, as shown and described.

DESCRIPTION

FIG. 1 is a rear view in perspective of an environmental enclosure for housing cellular RF equipment showing our new design;

FIG. 2 is a rear elevational view thereof;

FIG. 3 is a front elevational view thereof;

FIG. 4 is a right side view thereof;

FIG. 5 is a left side view thereof;

FIG. 6 is a bottom plan view thereof; and,

FIG. 7 is a top plan view thereof.
